UNITED STATES PATENT OFFICE

2,325,112

SPRAYER

Nicholas A. Constantine, Duluth, Minn.

Application April 11, 1941, Serial No. 388,075

3 Claims. (Cl. 299—88)

This invention relates to motor driven hand sprayers and has special reference to such particularly adapted for use in the spraying of insecticide, or the like.

The principal object of the invention is to provide a combined power and liquid container in the simplest manner possible.

Another object is to provide means in such a sprayer whereby the liquid therein is uniformly available to the pump mechanism thereof no matter at what angle the unit is held in the hands of the operator.

Other objects and advantages of the invention will appear in the following description thereof.

Referring now to the accompanying drawing, forming part of this application and wherein like reference characters indicate like parts:

Figure 1 is a central longitudinal section through one of the units showing portions thereof in elevation.

Figure 2 is a section on the line 2—2, of Figure 1.

Figure 3 is a view of a modified form of liquid pipe connection to the discharge pipe.

In the accompanying drawing, 1 represents an elongated hollow cylindrical casing, in which the operative portions of the unit are assembled, and in the rearmost end of this casing is installed in any desired manner a small electric motor, indicated at 2, the shaft of which is shown at 3. A transverse division wall is illustrated at 4 dividing the motor containing compartment of the casing from the liquid compartment 5, which is closed in any desired manner at its outermost end as at 6 and provided with any suitable form of filling opening and cap therefor, such, for example, as shown at 7.

An auxiliary spider-like head 8 is provided within the casing and spaced slightly to the rear of the wall 4 to form one suitable bearing for the motor 2, while at the opposite end of the motor compartment a similar spider-like head 9 is formed, as clearly illustrated in Figure 2, and which forms the other bearing for the motor. Intermediate of the heads 4 and 8 the casing is provided with any desired number and arrangement of ventilating holes 10 for the purpose of keeping the motor cool, and to further this purpose there is also provided at one end of the motor, the fan 11, which is shown as fixed to the motor shaft.

The motor shaft 3 at this end of the unit is designed to protrude entirely through the head 9 and carry thereupon the runner 12 of the small

compression pump, the outer cylindrical casing of which is illustrated at 13, which latter is fastened to the end wall 9 in any desired manner for example as by the screws 14.

The circumferential wall of the pump casing 13 is provided with a tangentially disposed air intake tube 15 and a port 16 leading through said wall into the compression chamber 17 of the pump. Just a short distance in advance of the intake portion 16 is a second smaller port 18 communicating with a suitable arrangement and valve controlled suction pipe 19 which leads forwardly of the unit and externally of the motor 2 into the liquid chamber 5, thence turned downwardly in any desired manner and connected as at 20 to the double suction pipe 21—22, which is fixed within what we will term the bottom of the unit, inasmuch as said unit is provided with a flat foot portion or bracket such as indicated at 23 to insure its ordinarily being positioned upright as shown.

The valve control for the pipe 19 is illustrated at 24 and obviously may be positioned anywhere desired without departing from the spirit of the invention.

Referring now to the double suction pipe 21—22, it is to be noted that the suction termini of these two pipes are identical and comprise a slight enlargement, as at 25, which terminates adjacent the pipe portion in a valve seat such as shown at 26 and just outwardly of which, within the enlargement, is a ball valve 27, which is held from dislodgment by a rivet or wire indicated at 28 transverse said enlargement, thus providing means whereby regardless of the position of the unit, if the valve 24 is open, and there is liquid in the unit, it will be taken up by the pump through the pipe 19. As further precaution against the ball 27 being abnormally sucked into the seat 26, I have provided one or more small relief orifices 40 which provides means for liquid more readily entering the enlargement just ahead of the ball and avoids such abnormal tendency towards closing in the event of excessive vibration or tipping of the unit. That is to say that under ordinary circumstances, whether the exhaust nozzle of the unit is pointed upwardly or downwardly or at any angle therebetween (except when rolled over), there will at all times be liquid available to the pump, and no matter which end is uppermost the valve therein will function to guard against the pump sucking air through that end which is not submerged in the liquid, thus, as is obvious, forming a very convenient means for insuring adequate

liquid supply to the pump under all ordinary circumstances.

The discharge pipe 30 from the pump extends longitudinally through the chamber 5 and outwardly as clearly shown at the front end thereof where it is equipped with any desired form of spray nozzle 32.

A novel feature of this unit is to be noted in the installation of the small by-pass pipe 29 leading from the discharge pipe 30 of the pump just back of the wall 4 of the chamber 5 and to the opposite side of said chamber and into same and along the uppermost wall thereof towards and reasonably close to the foremost end 6 of the unit; this pipe being secured in any desired manner to the uppermost wall for example as by a slight crook 31 therein which may be spot welded to said wall, or held thereagainst by its own inherent spring action, and thereby prevent undue vibration of same within the unit. This by-pass pipe is for the purpose of insuring air within the liquid chamber 5 under slight pressure and thus preventing any tendency of a vacuum being formed therein by the action of the pump.

The port 13 also leads into the compression chamber 17 and in which chamber the liquid when admitted thereto is thoroughly incorporated with the air drawn through the tube 15 and the thus mixed liquid and air is discharged through the port 34 into the discharge pipe 30.

It is thus evident that by such arrangement very accurate control of combined air and liquid may be accomplished by adjustment of the valve 24, in that the liquid in the container, whatever it may be, is admitted to the pump through the port 18; or by closing the valve 24 and operating the motor, only air would be discharged from the nozzle and which in some instances may be desired.

In Figure 3 is illustrated a modified form of liquid supply to the discharge pipe 30, and which clearly shows a more direct connection 35 intermediate of the discharge pipe and the two inclined pipes 21-22, said connection 35 terminating in the L-shaped reduced nozzle like portion 36 within the discharge pipe 30 and pointing to the discharge end thereof to result in a syphoning effect when air is passing through said discharge pipe and thereby draw the liquid from the branch pipes 21 and 22 in all respects similar to that previously described in respect to the liquid passing through the pump.

For convenient manipulation of the unit I have

illustrated a handle 33 fixed thereto, preferably closer to the motor end of the unit, for better balancing of same whether with or without liquid therein.

Having thus described my invention, what I claim and desire to secure by Letters Patent, is:

1. A motor-driven hand sprayer comprising an elongated casing, a division wall therein dividing the same into a motor and a liquid compartment, a motor within the motor compartment, a compression pump driven by said motor, means for conducting liquid from the liquid compartment to said compression pump, means admitting air to said pump, a discharge from said pump leading through said casing and terminating in a spray nozzle externally thereof, for the discharge of mixed liquid and air from said spray nozzle, and a relatively small bypass leading from said discharge to said liquid chamber to prevent the formation of a vacuum therein.

2. A motor driven hand sprayer, comprising an elongated housing, a division wall therein dividing the same into a motor and a liquid compartment, a motor within the motor compartment, a compression pump driven by said motor, a pipe for conducting liquid from the liquid compartment to said pump, means admitting air to said pump, a discharge from said pump leading to the forward end of said casing, for the discharge of mixed liquid and air from said spray nozzle, and a bypass from said discharge to said liquid compartment to provide pressure and prevent the forming of a vacuum therein.

3. A motor driven hand sprayer, comprising an elongated housing, a division wall therein dividing the same into a motor and a liquid compartment, a pair of spider-like heads in opposite ends of said motor housing, bearings centrally within said heads, a motor within the motor compartment and having an armature shaft extending within said bearings, a fan on said shaft between the motor and said outer head, a compression pump attached to said outer head and driven by said motor for mixing air and liquid therein and discharging same therefrom under pressure, means admitting air to said pump, means for the conducting of liquid from the liquid compartment to the compression pump, a discharge pipe leading from said pump to the forward end of said sprayer, and a bypass from said discharge pipe to said liquid compartment to provide pressure therein.

NICHOLAS A. CONSTANTINE.
